UNITED STATES PATENT OFFICE.

OLIVER O. RIESER, OF FOREST PARK, ILLINOIS, ASSIGNOR TO THE RICHARDSON COMPANY, OF LOCKLAND, OHIO, A CORPORATION OF OHIO.

DESIGN FOR A BATTERY BOX.

Application filed March 23, 1925. Serial No. 12,838. Term of patent 14 years.

To all whom it may concern:

Be it known that I, OLIVER O. RIESER, a citizen of the United States, residing at Forest Park, in the county of Cook and State of Illinois, have invented a new, original, and ornamental Design for Battery Boxes, of which the following is a specification, reference being had to the accompany-

ing drawing, forming part thereof.

The figure is a perspective view of the battery box, showing my new design.

I claim:

The ornamental design for a battery box as shown.

OLIVER O. RIESER.
